CLAIM

The ornamental design for a display fixture, as shown and described.

DESCRIPTION

FIG. 1 is a top perspective view of a display fixture according to an embodiment of the invention, with elements in dashed lines forming no part of the claimed design.

FIG. 2 is a bottom perspective view of a display fixture according to an embodiment of the invention, with elements in dashed lines forming no part of the claimed design.

FIG. 3 is a right side view of a display fixture according to an embodiment of the invention, with elements in dashed lines forming no part of the claimed design. A left side view is an identical mirror image of FIG. 3 and is omitted.

FIG. 4 is a front view of a display fixture according to an embodiment of the invention, with elements in dashed lines forming no part of the claimed design.

FIG. 5 is a rear view of a display fixture according to an embodiment of the invention, with elements in dashed lines forming no part of the claimed design.

FIG. 6 is a top view of a display fixture according to an embodiment of the invention, with elements in dashed lines forming no part of the claimed design.

FIG. 7 is a bottom view of a display fixture according to an embodiment of the invention, with elements in dashed lines forming no part of the claimed design; and,

FIG. 8 is a top perspective view of a display fixture, according to an embodiment of the invention, with elements in dashed lines forming no part of the claimed design.
